HAMMER RETARDER FOR AUTOMATIC FIREARMS

John C. Garand, Springfield, Mass.

Application September 11, 1946, Serial No. 696,330

5 Claims. (Cl. 42—69)

(Granted under the act of March 3, 1883, as amended April 30, 1928; 370 O. G. 757)

1

The invention described herein may be manufactured and used by or for the Government for governmental purposes, without the payment to me of any royalty thereon.

This invention relates to improvements in automatic firearms and is directed more particularly to improvements in firearms of the type commonly referred to as the U. S. carbine, Cal. .30, M1.

It is a principal object of the invention to provide a firearm of the automatic type, (especially of the carbine type, as stated) with a novel trigger group assembly which permits the same to be selectively placed in safe, semi-automatic firing, or full automatic firing conditions. As a special feature, the action within the trigger assembly is such that operation of the hammer of the firearm, when in full automatic firing condition, is delayed until the bolt member is fully locked, thereby insuring safety of operation during full automatic fire.

That is to say, the construction of the invention is so arranged that the operator of the firearm may readily select which of the said three conditions he desires and, furthermore, when the carbine is in full-automatic position, a delaying action is imparted to the movement of the hammer so that the firing pin will not be struck until sufficient time has elapsed to insure that the bolt is locked.

As will appear, the construction of the invention is also such that by altering certain conditions respecting particular parts about to be described, the rate of full-automatic fire of the arm may be decreased as desired. This feature, together with the ability to readily adjust the firearm to any of the conditions of safe, automatic or semi-automatic fire, obviously renders the firearm more flexible for military use and it is all accomplished without any appreciable increase in cost of manufacture or any difficulty in repair or replacement of parts.

The specific nature of the invention as well as other objects and advantages thereof will clearly appear from a description of a preferred embodiment as shown in the accompanying drawings in which:

Fig. 1 is a side elevational view, partly in section, of a receiver and trigger guard group of an automatic firearm embodying this invention. In this figure, the elements are shown with the hammer cocked, the trigger unpulled, and the selector set for semi-automatic fire.

Fig. 2 is a side elevational view, partly in section, of the trigger guard group taken from the

2

opposite side from Fig. 1. In this figure, the trigger is shown in its pulled position, the hammer in its fired position, and the selector set for automatic fire.

5 Fig. 3 is an elevational view of the selector.

Fig. 4 is a top elevational view of the inertia member.

Since the novel features of this invention are only concerned with the trigger group assembly, 10 the components of the bolt assembly, stock assembly, gas system, etc., have not been shown in the drawings. However, it will be understood that the combination of parts forming this invention is intended to cooperate with the conventional 15 operating parts of well known types of automatic firearms which are now in common use.

In Fig. 1 there is shown a receiver 2 having a trigger guard housing 4 with trigger 6 pivoted thereto on a pin 8. The usual trigger spring, indicated by 10, operates in the conventional manner biasing the rear end of the trigger downwardly. The top portion of trigger 6 is bifurcated as indicated at 12 and a sear 14 lies within the bifurcated portion and is pivotally mounted at its 20 center on pin 8. The mounting hole in the sear comprises an elongated slot 18 which permits limited longitudinal movement of the sear with respect to the trigger. A sear spring 20 cooperates between a suitable seat in the sear and in 25 the trigger to bias the sear forwardly with respect to the trigger.

A hammer member, shown at 22, is pivoted to the trigger guard, as by a pin 23, and is urged forwardly by a hammer spring 24 assembled on 30 a guide rod 25 in the usual way. The hammer member is provided with a slot or cut portion 26 in a side thereof. Immediately below slot 26 a forwardly facing cam surface 29 is provided on hammer 22 which is arranged to engage a cam 35 surface of an inertia member 44 which will be later described.

The forward end 15 of the sear is arranged to engage in a sear notch 17 provided in the end of 40 the cammed portion of the hammer. Thus, the hammer may be retained in cocked position by the sear.

What may be called a selector member 32 takes 45 the place of the ordinary so-called "safety." This 50 consists of a rod-like member which extends laterally through the housing at a point forwardly of the trigger and is adapted to control the pivotal movement of the trigger. That is to say, the rod or selector member 32 is movable in 55 a horizontal plane at right angles to the trigger

and other moving parts between three selective positions now to be explained.

The trigger has a forwardly and downwardly projecting portion 34 which cooperates with the selector to limit the pivotal movement of the trigger about the pin. First, there is a safety position wherein any substantial movement of the trigger is prevented; secondly, there is a semi-automatic firing position wherein the trigger may be pulled a limited extent; and thirdly, a full automatic position wherein the trigger may be pulled an additional distance beyond its limiting position for semi-automatic fire.

When the selector 32 is in its "safety" position, it is in such position relative to the forward downwardly depending arm portion 34 of the trigger member so that the latter will engage the peripheral surface 36 of the rod 32 and thereby prevent the trigger from moving sufficiently to trip the sear 14 to thereby release the hammer.

The selector 32 is provided with a vertical cut 40 therein so that when the rod is moved laterally from the safe position, said portion 34 of the trigger is permitted to move downwardly a certain amount as illustrated in Fig. 1. Thus, upon pulling or rearward movement of the trigger, the firearm fires semi-automatically. This is accomplished by virtue of the fact that the sear member 14 is thereby permitted to pivot sufficiently so as to disengage the cocked hammer and allow it to trip forward to strike the firing pin.

The rear portion of the trigger is provided with an upstanding projection 38 which underlies the rear end of the sear 14. When the selector is moved laterally slightly so as to be set for semi-automatic fire, the trigger may be pulled sufficiently that the projection 38 raises the rear end of the sear and disengages the front end 15 from the sear notch 17 in the hammer, thereby releasing the hammer to fire the cartridge. When the forward end of the sear disengages from the sear notch in the hammer 22 the sear moves forward slightly under the bias of sear spring 20 and such forward movement is sufficient to permit the rear end of the sear to slip off the trigger projection and return to its cocking position relative to the hammer. Thus, when the hammer is again rocked back by the recoiling motion of the bolt (not shown), the sear notch 17 in the hammer will again be engaged by the forward end 15 of the sear even though the trigger remains in the pulled position. When the trigger is released by the operator the sear is moved rearwardly with respect to the trigger due to the force of the hammer spring 24, which is much greater than that of sear spring 20. Thus the rear end of the sear again overlies trigger projection 38 so that pulling the trigger again will trip the sear in the manner described.

It is to be understood that the operations just described with respect to the safety and semi-automatic positions of the firearms do not deviate from the conventional mechanism, for example the trigger mechanism of the U. S. carbine Cal. .30 M1, except as will now be explained.

The selector 32 is provided with another vertical cut or slot 41 which is deeper than, and angularly displaced from, the previously mentioned cut 40. This obviously permits the trigger to be pulled still further rearwardly, upon further lateral movement, plus a slight rotation, of the selector.

This sets the selector in full automatic firing

position. The first shot is fired in the same manner as described for semi-automatic fire and the rear end of the sear slips off the trigger projection. However, the trigger now may be pulled an additional distance and this distance is sufficient that the top surface of the trigger engages the rear end of the sear and through this engagement the front end 15 of the sear is pivoted downwardly to a position where the sear notch 17 in the hammer is no longer contacted during the movement of the hammer from its fired to its cocked position. Thus in automatic fire the hammer is entirely free of the sear so long as the trigger remains pulled.

On what is virtually the opposite side of the selector 32 there is a cam slot 50 as shown in Fig. 3, which is adapted to receive one end portion of a longitudinally-extending plunger 52 held in spring-pressed relation between the selector member 32 and the conventional magazine lock member 54. The slot 50 preferably has three recesses or seats, such as 56, 58 and 60, with the third recess offset or disposed in the angular portion of the slot, as shown.

As will be apparent, this slot is arranged to cooperate with the structure of the opposite side of the pin in such a way that the latter is resiliently positioned in the selective manner above described.

The upper rear end of the housing (as shown) is provided with a horizontal cut or slot 30 which not only performs its usual function of cooperating with a mounting lug 31 of the firearm receiver 2 but also accomplishes a new purpose which will presently appear.

Pivoted to an upstanding portion 43 of the trigger member, as by pin 42, is what I prefer to call a weight of inertia member 44. This includes a body portion 46 which, according to the preferred form shown, is bifurcated so as to straddle the housing but it is to be understood that the shape or form of this portion is not as important as the fact that it is provided with sufficient mass so that it will delay movement of the hammer when the latter is in full automatic position as will be explained. In any event, the member also includes a rearwardly extending arm portion 47 having a cam surface 48 forwardly of its pivot point for engaging cam surface 29 of the hammer and its rear extremity is in the form of a dog 70 which is adapted to be received in the front end of the slot or recess 30 previously mentioned. Arm portion 47 of the inertia member lies in the path of the slot portion 26 of the hammer and hence does not add to the overall width of the trigger mechanism.

The inertia member may be pivotally biased in many ways but according to the preferred form shown, the usual trigger spring has one of its upper end portions, such as 74, extended to engage the arm portion 47 of member 44 and thereby, of course, urge it upwardly against the weight of the body portion 46; thus tending to move the cam surface 48 into the path of the hammer cam surface 29.

It will be noticed in Fig. 1 that when the firearm is in the semi-automatic firing position, the said dog 70 is seated in the recess 30 even when the trigger is pulled such that the dog thereby prevents any substantial movement of the weight member on its pivot. As a result, the weight 44 is prevented from affecting the operation of the hammer, although the latter is, of course, held against movement since the trigger cannot move. However, when the firearm is in its full automatic

fired position, as shown in Fig. 2, the dog 70 is withdrawn from recess 30 and the hammer is engaged and retarded by the inertia member through cooperative engagement of the cam surfaces 29 and 48 respectively.

This is accomplished by manually engaging head part 72 of the selector and rotating the same so as to allow the forward end portion 34 of the trigger to drop into the largest cut 41 thereof and thereby permit the inertia member to swing sufficiently on its pivot pin so that on pulling of the trigger, the dog 70 moves forwardly out of the slot permitting inertia member 44 to pivot forwardly under the bias of spring arm 74 which will dispose the cam surface 48 on the inertia member in the path of cam surface 29 on the hammer. The consequent result is that the hammer does not immediately follow the bolt forwardly but strikes the firing pin after a delay sufficient to insure that the bolt is locked.

It will thus be seen that by selection of the mass of the inertia member, the rate of fire may be decreased as desired. In addition, by varying the angle of the cam surface 48 and/or the tension of the spring arm 74, it is possible to further delay the action of the hammer to a considerable extent and thereby achieve still further reduction in rate of fire.

As will be appreciated, while the operator of the firearm may adjust the firearm to any one of three conditions, the inertia member functions only when the selector is in its full automatic position. In the safe or automatic positions, the trigger cannot be pulled sufficiently to move the cam surface 48 of the inertia member forwardly in front of cam surface 29 on the hammer. In these positions, the dog member 70 lies in the rear assembly slot 30 of the trigger housing member, and thus prevents pivotal movement of inertia member 44 under the bias of spring arm 74.

I claim:

1. In an automatic firearm having a spring pressed hammer movable between a cocked and a firing position, a sear engageable with said hammer to retain said hammer in the cocked position, trigger means for moving said sear to a non-engaging position relative to said hammer, an inertia member movably mounted on the firearm and disposed in the path of said hammer as said hammer moves to its fired position, and cam means on said hammer engageable with said inertia member to move it out of the path of said hammer whereby the firing movement of said hammer is delayed.

2. In an automatic firearm having a spring

pressed hammer movable between a cocked and a firing position, a sear engageable with said hammer to retain said hammer in the cocked position, trigger means for moving said sear to a non-engaging position relative to said hammer, an inertia member movable by said trigger means into the path of said hammer as said hammer moves to its fired position, and cam means on said hammer engageable with said inertia member to move it out of the path of said hammer whereby the firing movement of said hammer is delayed.

3. In an automatic firearm having a spring pressed hammer movable between a cocked and a firing position, a sear engageable with said hammer to retain said hammer in the cocked position, a trigger operatively connected to said sear for moving said sear to a non-engaging position relative to said hammer, an inertia member pivotally connected to said trigger and movable by pulling movement of said trigger into the path of said hammer as said hammer moves to its fired position, and cam means on said hammer engageable with said inertia member to move it out of the path of said hammer whereby the firing movement of said hammer is delayed.

4. In an automatic firearm having a spring pressed hammer movable between a cocked and a firing position, a sear engageable with said hammer to retain said hammer in the cocked position, trigger means for moving said sear to a non-engaging position, a trigger movably mounted on the firearm, means for selectively limiting the pulling movement of said trigger to either a semi-automatic firing position or an automatic firing position, means connecting said trigger and said sear for moving said sear to a non-engaging position relative to said hammer in said automatic firing position of said trigger, an inertia member pivotally connected to said trigger and pivotable by movement of said trigger to its said automatic firing position into the path of said hammer as said hammer moves to its fired position, and cam means on said hammer engageable with said inertia member to move it out of the path of said hammer whereby the firing movement of said hammer is delayed.

5. The combination defined in claim 4 and including means for preventing pivotal movement of said inertia member into the path of said hammer as said trigger is pulled to its semi-automatic firing position.
